UNITED STATES PATENT OFFICE

144,134

DESIGN FOR A TOY HORSE OR SIMILAR ARTICLE

Kay Perper, New York, N. Y.

Application August 24, 1945, Serial No. 121,626

Term of patent 3½ years

(Cl. D34—2)

To all whom it may concern:

Be it known that I, Kay Perper, a citizen of the United States of America and a resident of the Borough and county of the Bronx, in the city and State of New York, have invented a new, original, and ornamental Design for Toy Horse or Similar Article, of which the following is a specification, reference being had to the accompanying drawing, forming a part thereof, in which

Fig. 2 is a rear elevational view thereof;

Fig. 3 is a front elevational view thereof; and

Fig. 4 is a top plan view thereof.

I claim:

The ornamental design for a toy horse or similar article, as shown.

KAY PERPER.
